UNITED STATES PATENT OFFICE.

NELSON KEMENER DE LAFLAME, OF PLATTSBURG, NEW YORK.

POTATO-DIGGER.

SPECIFICATION forming part of Letters Patent No. 316,949, dated May 5, 1885.

Application filed July 19, 1884. (No model.)

To all whom it may concern:

Be it known that I, NELSON KEMENER DE LAFLAME, a citizen of the United States, residing at Plattsburg, in the county of Clinton 5 and State of New York, have invented certain new and useful Improvements in Potato-Diggers, of which the following is a specification, reference being had therein to the accompanying drawings.

10 My improvements consist in certain novel features of construction and arrangement which will first be described, and afterward particularly pointed out in the claims, reference being had to the accompanying drawings, in which—

15 Figure 1 is a side elevation of a machine embodying my improvements. Fig. 2 is a top plan view thereof. Fig. 3 is a transverse vertical section on the line $x-x$ of Fig. 1. Fig. 4 is a detached detail view of the scoop or plow. Fig. 5 is a detail view showing means for rotating the axle when the machine is moved forward. Fig. 6 is a side elevation of the main machine detached from the assorting attachment.

20 The same letters refer to like or corresponding parts in all the figures.

25 A A are the carrying-wheels, journaled upon the ends of an axle, B, and engaging therewith in their advancing movement, so as to cause it to revolve by means of the spring-becking ratchets C, which may be of the usual or any preferred construction. Mounted on this axle are two strong vertical brackets, D, 30 formed at their lower ends with suitable journal-bearings and removable caps d, bolted thereto, through which the axle B passes freely, and at their upper ends the brackets D are bolted to the main frame E.

35 F is the driver's seat; G, the draft-pole.

The frame E is provided with rigid hangers H, one at each side, near the rear end, said hangers furnishing bearings for spindles i of the rear roller of the gathering-belt N. Hung 40 freely from the spindles i are the suspending-arms k, to which the rear ends of the side guards, K, are rigidly secured, while their forward ends are rigidly united by the scoop or plow, and are provided at each side of the machine with a rigid arm, M, curved upon an arc 45 concentric with spindles i i, and having gear-teeth formed on their outer edges that are engaged by small pinions l l, rigidly secured at

each end of a shaft, L, journaled transversely beneath the front end of the main frame. A 55 drum, l', is secured upon one end of this shaft, preferably the right-hand side, inside of the hanger supporting that end of the shaft, and upon this drum is wound a chain or cord, 12, the other end of which is attached to a hand-lever, Q, which is secured at any desired point of adjustment by means of a spring-pawl, q, engaging a curved rack, R. By this means the driver is enabled to adjust the plow and gatherer any required height, both sides being 60 raised simultaneously and equally.

The forward roller, I', of the gathering-belt N has its bearings in boxes S', adjustably secured to the forward ends of two curved arms, S, the rear ends of which are hung upon the 70 spindles i of the rollers I. The arms S are downwardly curved to pass under the axle.

In order to insure the equal rise and fall of arms S to maintain the roller I' in planes parallel to that of the plow and grate, I provide 75 a small shaft, T, journaled at each end in one of the arms S, between the axle B and the roller I'. On this small shaft, at each end thereof, are keyed two pinions, s s, which engage at equal heights the two racks M' M', 80 rigidly secured to the side guards and curved upon the arc of circles concentric with spindles i i, so that both arms S are compelled to rise and fall simultaneously and equally, and maintain the relation of the gathering-belt to 85 the plow and grate as said parts are adjusted up or down.

Sustaining-rollers U for the scoop and gatherer are journaled to the lower ends of arms u u, at each side, which are adjustably secured 90 by means of set-screws to the lower portions of rack-arms M. These adjustable rollers prevent the scoop from running too deep into the ground, and also determine the depth to which the scoop operates when in operation.

The scoop or plow V is formed as a thick flat blade with a front cutting-edge beveled on the under side, curving forward from the sides to form a rounded forwardly-projecting edge in the middle, as shown. On the upper surface of this portion is formed a pointed, angular, V-shaped dividing ridge, W, presenting obliquely-inclined faces at each side, and rising rearwardly as well as increasing in width, so as to more completely break up the 100 material. This form of plow acts in the man-

ner of a wedge, breaking up and dividing the earth, and so preparing it for the operation of the belt and grate. The rear face of this ridge is sloped off rearwardly upon a curve concentric with the sweep of the teeth of the gathering-belt.

The inclined gathering-grate X is composed of longitudinal rods of thick wire spaced apart, so as to let the teeth of the gathering-belt pass between them, and are curved upward at their rear ends (not shown in the drawings) to conform to the upward bend of the gathering-belt as it passes over the roller I. Said grate is preferably made concave in cross-section to throw the potatoes toward the middle, and is attached at its forward end to the bar x, pivoted at its ends in the side boards, K K, just in rear of the plow V. At its rear end the grate is supported at each side upon the arms y y of the transverse rock-shaft Y, the ends of which project through the side guards, K K, and are provided with a second pair of rock-arms, y' y'. The ends of these bear against flat springs l l, secured to the inclined faces of lugs or brackets z z, formed on or secured to the upper rear ends of the side guards, K K. It will be seen that if an unusual accumulation of material takes place between the gathering-belt and the grate the latter will yield downwardly and permit the potatoes to pass without injury.

The gathering-belt N is constructed as a close endless apron of canvas, leather, or other suitable material, and provided with round-pointed, L-shaped, elastic sheet-metal teeth 5, the bottom of the L forming the base, whereby the tooth is secured, by rivets or otherwise, to the belt. They are presented flatwise to the potatoes, and their round points and elastic yield 40 to prevent them from cutting or bruising the potatoes. The teeth 5 are arranged in curved rows concave in the direction of advance, as shown, corresponding in some degree to the form of the front edge of the plow, and co-45 operating with the concavity of the grate to gather the potatoes from each side of the ridge W toward the middle, while said teeth, being of a length to project between the bars of the grate to some extent at the sides, compensate 50 for its concavity and prevent the escape back to the front of any potatoes. For operating this gathering-belt a pinion, Q', is keyed upon the right-hand end of the shaft, having the spindles i of the upper roller outside of the 55 hanger H. This pinion meshes with a large internal-gear wheel, 3, mounted loosely upon the axle between the main frame and the right-hand carrying-wheel, and is formed with a clutch-faced hub, 4. A clutch-faced collar, 8, 60 engaging the axle, so as to revolve therewith, by means of a rib, groove, or spline, permitting it to slide back and forth on the axle, so as to engage or disengage the hub of the internal-gear wheel, 3, is controlled by means of a ring, 6, surrounding the collar, and a rod, 7, 65 sliding back and forth in bearings on the brackets D. This rod is connected with a

bell-crank foot-lever, F⁵, nearly under the driver's seat, by means of a rod, S', and lever 9, so that the gathering-belt may be thrown into and out of operation at will by the driver's foot by causing the engagement or disengagement of the axle and the internal gear-wheel, 3. 70

At the left-hand side of the machine, on the projecting end of the shaft i, is keyed a pulley, 10, which is designed for communicating motion by a belt to a cleaning and sorting attachment used under some circumstances. The cleaning and sorting attachment is mounted on a supplemental frame comprising two pairs of upwardly and downwardly curved arms, a a', detachably bolted to the upper and under sides of the rear ends of the side bars of the main frame by means of through bolts and nuts, as shown, and a pair of horizontal sills, b, similarly bolted to the rear ends of the downwardly-curved pairs of arms a', and supported upon a pair of caster-wheels, c c. The horizontal sills b carry a platform, b'.

Journalized upon the lower and upper arms a a' of this supplemental frame are rollers, that carry a toothed belt, e, similar to the gathering-belt N, said pulleys being driven from the pulley 10, before mentioned. (See Fig. 1.) The teeth of this belt e sweep up a steeply-inclined floor, f, formed of a series of rods similar to the grate X, the curved lower end, f', of which is connected with the gathering-grate by hooking the bent ends of its component rods over the cross-rod 12 at the upper end of the said gathering-grate K, and between the component rods of the grate X, as shown in Fig. 1.

Upon the outer ends of the upwardly-curved arms a are rigidly secured two horizontal bars, b², in which are journaled two rollers, 16 and 17, that carry a horizontal toothed endless apron, e'. Two vertical standards, b³, extend upwardly from the arms a, in which is journaled a toothed roller, b⁴. The apron e' moves in a direction opposite to that of the belt E, it being driven by a crossed belt from the upper roller of said toothed belt e, while the toothed roller b⁴ rotates in the direction of the arrow m in Fig. 1. The potato tops and stalks, which are brought up by the teeth of the belt e, are received by this toothed roller and apron and delivered out beyond the tail of the machine, while the potatoes roll out from the teeth of the elevator-belt upon an inclined grate. The smaller potatoes fall through and are conducted by the hopper o' beneath into the receptacle w, while the larger roll over the tail of the grate through the hopper o² into the receptacle w'. More than two sorts or grades may be made, if desired, by having additional grates and receivers.

It is to be understood that this attachment may be dispensed with when the machine is used in stony ground or elsewhere when its use is not desired. In this case a converging spout may be attached at the rear end of the gathering-grate and the potatoes delivered in a row upon the ground.

Modifications in details of construction may be made without departing from the principle or sacrificing the advantages of my invention; and I would therefore have it understood that 5 I hold myself at liberty to make such changes and alterations as fairly fall within the scope of my invention.

Having thus fully described my invention, what I claim, and desire to secure by Letters 10 Patent of the United States, is—

1. In a potato-digger, the main frame mounted upon an axle adapted to be rotated by the forward movement of the carrying wheels, the rear roller of the gathering-belt journaled in 15 hangers depending from the rear end of the main frame, the forward roller of the gathering-belt journaled in the forward ends of arms pivoted to and extending from the journals of the rear rollers, and the gathering-belt, in combination with the plow or scoop pivotally connected at its rear end to the journals of the rear roller of the gathering-belt, and adapted to be adjusted at its forward end nearer to or farther from the frame, and means, sub- 20 substantially as described, for adjusting the forward roller of the gathering-belt nearer to or farther from the plow or scoop, as and for the purpose set forth.

2. In a potato-digger, the main frame mounted 30 upon suitable carrying-wheels, the rear roller of the gathering-belt journaled in hangers depending from the frame at the rear thereof, the side arms pivoted to the journals of the rear roller and forming bearings at their forward ends for the journals of the forward roller of the gathering-belt, the gathering-belt provided with teeth and supported and operated by the rollers, the shaft extending from one to the other of the forward roller-supporting 35 arms journaled in said arms and provided at each end with pinions, in combination with rack-arms extending upwardly from the side guards of a plow or scoop, pivotally connected to the journals of the rear roller of the carrying-belt and having its forward end adjustable nearer to or farther from the frame, substantially as described, and for the purpose set forth.

3. In a potato-digger, a main frame mounted 50 upon carrying-wheels adapted to be clutched with and thereby rotate the axle in their forward movements, said frame pivotally connected at its rear end to a combined grate and plow or scoop located beneath the frame and having its forward end adjustable nearer to or farther from the frame, in combination with the gathering-belt supported and operated by rollers journaled in hangers depending from the frame, and inside arms, pivoted at their rear 55 ends to said hangers, and means located below the main frame, substantially as described, for adjusting the belt nearer to or farther from said grate and plow, as and for the purpose set forth.

65 4. In a potato-digger, a frame supported upon an axle journaled in carrying-wheels, and provided at its rear end with depending

hangers in which is journaled the rear roller of the gathering-belt, in combination with the combined grate and plow or scoop located 70 below and pivotally connected to the journals of the rear roller of the carrying-belt, and provided at its forward end with upwardly-projecting curved rack-arms concentric with the journals of said rear roller of the gathering-belt, pinions engaging said rack-arms and mounted upon a shaft journaled to the forward end of the frame, and guide-wheels adjustably connected to the lower end of the said curved arms, substantially as described, and for the 80 purpose set forth.

5. In a potato-digger, the combination of the gathering-belt mounted upon suitable rollers, the side guards of the plow or scoop, the grate pivoted at its forward end in said guards, 85 with a rock-shaft extending from one to the other of said guards, and provided with means, substantially as described, for adjustably supporting the rear end of the grate and permit it to yield when under too great pressure, as and for 90 the purpose set forth.

6. In a potato-digger, the combination of the gathering-belt mounted upon suitable rollers, the side guards of the plow or scoop, the grate pivoted at its forward end in said guards 95 and resting at its rear end upon spring-pressed rock-arms projecting from a rock-shaft extending from one to the other of and journaled in said guards and controlled by said rock-arms, substantially as and for the purpose set forth. 100

7. The combination, in a potato-digger, of a yielding grate for receiving the potatoes and a gathering-belt having yielding teeth, substantially as set forth.

8. The combination, with the potato-digger 105 frame and grate, of a supplemental attachment consisting, essentially, of a frame provided with a toothed elevator-belt, a grate for receiving and sorting the potatoes, and a toothed belt and picker for receiving and discharging 110 separately the vines and stalks, substantially as set forth.

9. The combination, with the frame and grate of a potato-digger, of the detachable supplemental frame supported at its rear end upon 115 caster-wheels, and provided with a platform located directly below the assorting-grate to receive removable receptacles for the sorted potatoes, the assorting-grate, the elevator, and means for driving the elevator-belt from the 120 digger, substantially as and for the purpose set forth.

10. The combination of the inclined grate-floor, the inclined toothed elevating-belt, the assorting-grate, the toothed endless apron 125 above the assorting-grate, and the picker above the apron, substantially as set forth.

In testimony whereof I affix my signature in presence of two witnesses.

NELSON KEMENER DE LAFLAME.
